UNITED STATES PATENT OFFICE

HERBERT GEORGE KAMRATH, OF FLINT, MICHIGAN, ASSIGNOR TO A C SPARK PLUG COMPANY, OF FLINT, MICHIGAN, A COMPANY OF MICHIGAN

AIR CLEANER

Application filed April 23, 1927. Serial No. 186,083.

This invention relates to air cleaners of the type employed on internal combustion engines to clean the air supplied to the cylinders. The cleaner is of the type in which dust particles are separated by centrifugal action. The specific cleaner illustrated was designed for use upon motor-cycles and is consequently marked by simplicity and economy in construction. In general the cleaner is similar to that described and claimed in my prior application Serial No. 53,341, filed August 29, 1925, now Patent No. 1,723,427 issued August 6, 1929. It is distinguished from that cleaner in that a tangential dust outlet is provided instead of an axial outlet so that dust is more effectively discharged; in that a special clip is provided to render the cleaner easy of attachment to the engine; and in the inclusion of several other features of improvement which will be pointed out in the specification and covered by the appended claims. In the drawings Figure 1 is a view showing my cleaner applied to a motor-cycle engine, the one illustrated being of the well known Harley Davidson make. Figure 2 is a sectional view through the cleaner. Figure 3 is a view taken on line 3, 3 of Figure 2. Figure 4 is a detailed perspective view of the securing clip. Figure 5 is a detail view of the dust outlet. In Figure 1, 6 indicates the motor-cycle engine, 8 the carburetor and 10 a passage conducting fuel mixture to the engine cylinders 12. The carburetor 8 is provided with an intake conduit 14 and 16 indicates my improved cleaner mounted on the intake.

The cleaner consists of a cylindrical casing 18 having an open end 20 and a closed end 22. In the open end 20 is fitted stamping 24 formed to provide a plurality of blades 26 arranged in an annular series about a central dome 28. These blades may be of the configuration described in my prior application Serial No. 157,761 filed December 29th, 1926, now Patent No. 1,729,390 issued Sept. 24, 1929. The stamping 24 may be secured in place by forming its edge 30 over the flange 32 formed in the open end of the casing 18 or, if desired, the flange 30 may be omitted and the stamping secured in position by bolt

34 and nut 36, the bolt being secured at its other end to air straightener 38 suitably anchored in the clean air discharge conduit 40 extending into the open end of the cleaner by means of bolt 42 passing through aligning apertures in the conduit 40 and the straightener.

To secure the cleaner to the conduit 14 I have secured to the rear wall 22 of the cleaner casing a clip 44 comprising an annulus 46 surrounding the conduit 40 and having rearwardly extending spring arms 48 extending substantially parallel with the conduit. The outer ends of the clips are shown bent outwardly as at 50 to facilitate assembly. The clip 44 is secured to the rear wall of the casing by rivets 52 although any other form of securing means such as welding may be substituted if desired.

The intake conduit 14 is provided with a terminal bead 15 and if desired, the spring arms 48 may be shaped to follow the contour of the bead and to firmly grip the latter, thereby holding the cleaner in place. However, I prefer to employ positive means for clamping the arms to the conduit. This means may take the form of a strap or clamping band 17 encircling the arms as shown in Figures 1 and 2. The strap may be drawn up to clamp the arms about the conduit by manipulating a bolt and nut, or other securing means connecting the ends of the band as shown at 19 in Figure 1.

The casing 18 is provided with a dust outlet 54. This outlet is formed by cutting the metal of the casing along intersecting lines 56 and 58 and bending the resulting tongue 60 outwardly as shown in Figure 5.

The cleaner operates as follows: The air upon striking the blades 26 is set whirling causing dust particles to be thrown outwardly and when the whirling column reaches the dust outlet 54 the particles are discharged by virtue of their momentum. The column of air thus relieved of its dust content reverses its direction and then reverses a second time and, striking the straightener 38, its line of flow is changed from spiral to rectilinear and the air now passes into the carburetor intake 14. The

baffle 54 prevents stray air currents from passing in through the dust outlet, the portion 60 serving as a cowl.

The spring fingers 48 of the clip 44 are locked in engagement with conduit 14 by strap 16 and the cleaner is thus securely held in position free from rattling. With the design of clip shown the air cleaner casing is strengthened at the point of connection with the air outlet.

10 While I have shown and described the preferred form of my cleaner it is obvious that my invention is capable of a considerable amount of modification as indicated by the scope of the appended claims.

15 I claim:

1. An air cleaner comprising a cylindrical casing having an open end and a closed end, a member closing the open end of the cleaner and comprising a central imperforate portion and an annular series of helical blades surrounding the imperforate portion and adapted to impart a whirling motion to the entering air, an axial clean air outlet extending into the casing through the closed end, and a relatively short aperture in the side wall of the casing adjacent the closed end and opening into the atmosphere, and a shield for said aperture, and an air straightener arranged in the casing adjacent the outlet tube for removing the whirl from the outgoing air.

2. An air cleaner comprising a casing having a clean air outlet adapted to register with an intake conduit and a plurality of resilient arms adapted to be secured to the casing and extending rearwardly therefrom for encircling and yieldingly gripping the conduit, and a clamping band adapted to encircle the ends of the arms and clamp them to the conduit.

35 In testimony whereof I affix my signature.
HERBERT GEORGE KAMRATH.
